TRUING DEVICE FOR FRUIT JAR COVERS

Henry S. Lubben, Le Mars, Iowa

Application May 29, 1935, Serial No. 24,049

1 Claim. (Cl. 81—15.1)

My invention relates to a device for correctly reshaping and truing fruit jar covers.

An object of my invention is to provide such a device which will accurately and positively reshape the lower flange of a jar cover so that it will seat accurately upon the rubber gasket.

A further object of my invention is to provide such a device which will cause a positive, accurate centering thereon so that the truing operation will be accurate within very close clearances.

A further object of my invention is to provide means for truing the threads of the jar cover in connection therewith.

A further object of my invention is to provide means for causing pressure to be applied directly against the flange and to retain the jar cover in locked position during this operation.

A further object of my invention is to provide the above mentioned means in a construction of great simplicity which can be manufactured at a very reasonable cost.

With these and other objects in view, my invention consists in the construction, arrangement and combination of the various parts of my device, whereby the objects contemplated are attained, as hereinafter more fully set forth, pointed out in my claim, and illustrated in the accompanying drawing, in which:

Figure 1 is a plan view of the device,

Figure 2 is a sectional view taken generally medially thereof, and

Figure 3 is an enlarged detail of a part thereof.

In using jar covers, the lower seating flange of the jar covers usually become bent or distorted to a certain extent due to unequal pressures being exerted or by being damaged during the normal handling of the same. As a result when such a cover is used against its gasket, the jar will not be sealed properly due to the unequal pressure, and there will be a tendency for the rubber gasket to be squeezed at the particular location of the raised portion of the flange. It is, therefore, necessary to provide a truing device which will reshape this flange so that when the jar cover is screwed on against the rubber gasket, the pressure will grip the gasket practically simultaneously so that this effect will not occur.

Furthermore, since the jar cover rim is very small in breadth, it is necessary to provide accurate centering means so that the flange will be gripped positively at all points.

The base member is indicated generally by the character 10, and includes the raised boss 11 having the cylindrical cavity 12. The boss 11 is also

cylindrical, and includes the accurately formed sides 13. Merging with the sides 13, is the beveled portion 14 which terminates in the portion 15 which includes male threads 16 adapted to conform closely to the threads in a standard fruit jar cover. It will be understood that the base member 10 can be formed integrally as shown or in any other suitable way, although the preferred form, as shown, shows the form having the integral features of a single casting, preferably made of aluminum or other metal. The base can also be hollow as shown and having the side walls 17 which act as ribs for the structure to strengthen the same.

The usual jar cover 18 which includes the porcelain or glass insert 19 is screwed down tightly on the threads 16 so that the small flange 20 of the jar cover will rest against the beveled shoulder 14. The top member 21 is then placed downwardly over the jar cover. This member includes the cylindrical handle 22, the strengthening ribs 23, the lower annular member 24, which merges with the beveled portion 25, the beveled portion 25 to be exactly parallel with the further beveled shoulders 14 of the base member. The member 24 terminates in the lower ring portion 26, which is closely machined to fit the sides 13 with an extremely small clearance therebetween. Figure 3 shows an enlarged detail of this portion of the device, showing the small clearance, which feature is an important part of my invention.

In reshaping the flange 20 of the jar cover 18, the device 21, as stated, is placed over the cover and the handle 22 is firmly grasped with the hand, and a firm and positive pressure is applied downwardly against the base member, at the same time rotating the upper member 21. Since by virtue of the ring shaped member 26 the device will be very closely centered, the small flange 20 will be accurately reshaped, and all the indentations or raised portions will be merged into a uniform level surface. If the centering means were not provided this function could not occur due to the errors involved.

The member 24 includes the cylindrical walls 27 which are of practically the same diameter as the threads in the jar cover. The reason for this is that when the upper piece is forced downwardly this portion will tend to straighten out threads which may have also become distorted through use, so that as a result the entire jar cover is reshaped accurately. The positive, downwardly, and rotational pressure exerted by means of the upper piece against the lower piece re-

sults in a positive truing device which reshapes the flange and the jar cover so that it will seat perfectly against the usual rubber gasket.

It will be observed further that the jar cover by being screwed by the threads to the lower member is held rigidly and can not be turned since the rotational pressure is exerted in the direction of the threads. The harder the upper piece is turned, the more positive will become the locking of the jar cover. This is necessary to secure a relative movement between the pieces in order to effect the best truing results.

It will now be seen that I have provided a truing device for jar covers which will positively and exactly reshape the lower flange of a jar cover, which will provide accurate centering means for the same during this operation, which reshapes the entire jar cover ready for use, and which allows a convenient application of pressure directly above the work to be done.

It will be seen further that I have provided all the above mentioned means in a structure of great simplicity which can be manufactured at a very reasonable cost.

Some changes may be made in the construction and arrangement of the parts of my invention without departing from the real spirit

and purpose of my invention, and it is my intention to cover by my claim any modified forms of structure or use of mechanical equivalents, which may be reasonably included within their scope.

I claim as my invention:

A fruit jar cover truing device comprising a cylindrical base member including a beveled shoulder extending from said base member, continuation of said shoulder including threads adapted to be received within the threads of a fruit jar cover and to cause the fruit jar flange to be seated upon said beveled shoulder, an upper rotatable member having a further beveled shoulder adapted to firmly compress said fruit jar flange against the said base member shoulder, and said upper member including an annular ring extension directly adjacent said second mentioned beveled shoulder, the extension being adapted to closely receive the periphery bounding said base member shoulder to provide accurate centering means thereon, and said upper member including a pair of upstanding ribbed flanges, a cylindrical handle attached between the flanges.

HENRY S. LUBBEN.
